UNITED STATES PATENT OFFICE.

JERRY R. SMITH, OF CHICAGO, ILLINOIS.

SHOE-FASTENER.

1,371,941.

Specification of Letters Patent. Patented Mar. 15, 1921.

Application filed July 27, 1920. Serial No. 399,285.

To all whom it may concern:

Be it known that I, JERRY R. SMITH, a citizen of the United States, residing at Chicago, in the county of Cook and State of Illinois, have invented new and useful Improvements in Shoe-Fasteners, of which the following is a specification.

This invention relates to devices for closing the meeting edges of shoes, boots, or the like, and has for its object the provision of novel fastening means designed to avoid the use of buttons and button-holes, eyelets and laces, or other similar devices.

An important and more specific object is the provision of a shoe fastener which includes strips secured upon the meeting edges at a shoe opening and an elastic tongue carrying hooks arranged in spaced relation and engageable with said strips, the strips being furthermore provided with notches within which certain of the hooks may be engaged for forming a lock to prevent displacement of the parts.

An additional object is the provision of a securing device of this character which will be simple and inexpensive in manufacture, highly efficient in use, easy and quick to fasten, and a general improvement in the art.

With the above and other objects and advantages in view, the invention consists in the details of construction to be hereinafter more fully described and claimed and illustrated in the accompanying drawings in which—

Figure 1 is a front elevation of a shoe equipped with my fastening device, showing the shoe in closed position,

Fig. 2 is a similar view showing the shoe in open position,

Fig. 3 is a longitudinal sectional view,

Fig. 4 is a cross sectional view,

Fig. 5 is a detail perspective view of the tongue,

Fig. 6 is a detail perspective view of one of the strips, and

Fig. 7 is a perspective view of one of the hooks.

Referring more particularly to the drawings, the letter A designates a shoe and B designates the meeting edges of the opening therein.

In carrying out my invention I provide metallic strips 10 which are secured upon the edges B and these strips are channeled longitudinally, as shown. At their upper ends

the strips are formed with humps 11 adjacent which are notches 12.

The numeral 13 designates the tongue which may have its lower end secured within the shoe in the usual manner and which has its upper end formed with a tab 14 serving as a handle. This tongue is formed of elastic material and carries two sets of hooks 15 which are arranged at intervals with the hooks in one series in spaced relation to the hooks of the other series, the hooks being arranged with their bills 16 extending toward one another.

In the use of the device it will be seen that when the shoe is in open position, that is ready to be slipped onto the foot of the wearer, the tongue 13 is in its lowermost position so that all the hooks 15 will be disposed toward the lower ends of the strips 10 so that the edges B may be pulled apart to permit the insertion of a foot. When it is desired to close the shoe or fastening it is merely necessary that the operator grasp the tab 14 and pull the tongue 13 upwardly, as clearly shown in Fig. 1, whereupon the hooks 15 will slide upwardly along the strips 10. Owing to the elasticity of the tongue, the strips 10 will be drawn together closing the shoe. When the tongue is pulled upwardly, as far as possible, the uppermost hooks 15 will be pressed outwardly over the humps 11 and will then snap into the notches 12 and consequently hold the tongue in such upper position and prevent downward slipping.

From the foregoing description and a study of the drawings it will be apparent that I have thus provided a simply constructed and easily applied shoe fastening device which is easily operated and which will be not only secure in its holding action but which will be prevented from casual displacement.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. In combination with the meeting edges of a shoe opening, a fastening device comprising a pair of strips secured upon said

meeting edges and formed with channels, an elastic tongue secured at its lower end within the shoe, and a plurality of spaced hooks carried by the tongue and slidably engaging 5 said strips.

2. In combination with the meeting edges of a shoe opening, a fastening device comprising a pair of strips secured upon said meeting edges and formed with channels, an

elastic tongue secured at its lower end within the shoe, and a plurality of spaced hooks carried by the tongue and slidably engaging said strips, said strips being formed at their upper ends with humps and notches to serve as locking means for the uppermost hooks. 10 15

In testimony whereof I affix my signature.

JERRY R. SMITH.
